LOCOMOTIVE TENDER

Edwin Archer Turner, New York, N. Y., assignor
to The Standard Stoker Company, Incorporated,
a corporation of Delaware

Application July 22, 1932, Serial No. 623,960

6 Claims. (Cl. 105—234)

This invention relates to railway rolling stock and consists in a novel tender structure of the type equipped with a fuel conveyor of a stoking device.

5 The present tendency in railroad operation is toward the adoption of extended and faster locomotive runs. To this end all unnecessary stops are eliminated, but stops must be made to replenish the supply of coal and water. Reduction 10 of the number of such stops materially increases the running time of the trains. This invention has for its main object the provision of a locomotive tender of greater coal and water capacities than tenders of past practice whereby 15 longer runs may be made with less frequent stops for refueling.

Other objects of the invention reside in the relation and arrangement of the tender coal and water compartments with the fuel conveyor and 20 in the provision of a novel and improved conveyor peculiarly adapted for use with the locomotive tender of the invention. These objects and the advantages of the invention will be apparent from the following description when read in connection 25 with the accompanying drawings, wherein,

Figure 1 is a central vertical longitudinal section through the front end portion of the locomotive tender embodying the present invention;

Figure 2 is a plan view of Figure 1 taken in section 30 on the line 2—2 thereof;

Figure 3 is a transverse cross section through the fuel conveyor on the line 3—3 of Figure 1;

Figure 4 is a fragmentary enlarged sectional view taken on the line 4—4 of Figure 2; and

35 Figure 5 is a similar vertical sectional view taken on the line 5—5 of Figure 2.

On the drawings, 10 represents the locomotive tender as a whole. It is provided with a water bottom underframe 11, the coal bunker 12 and the water compartment 13. A stoker fuel conveyor trough 14 is formed with the side partition plates 15, the rear partition plate 16 and the front wall 17 of the tender to form a water tight partition 40 between the coal bunker and the water compartment, and to provide a closure for the latter at the front end of the tender.

Instead of providing the usual stoker compartment to house the fuel conveyor, the present invention contemplates forming the conveyor trough 14 within the water compartment 13 in a manner to provide a space as at 18 between the underside of the trough and the top wall 19 of the underframe to permit the circulation of water 45 from one side of the tender to the other. This

construction materially increases the water carrying capacity of the tender.

The coal bunker 12 is substantially the same width and height as that provided in the conventional form of tenders but its overall length has been increased as much as possible permissible with the size controlling factors such as turntables, engine stalls and like equipment. In a tender of this lengthened form the stoker conveyor necessarily must be much longer and in 20 some instances, twice the length of the longest conveyor heretofore used. The drawings disclose a conveyor substantially twenty-five feet long. With this length of conveyor, it is impractical to form the fuel advancing means of a one piece 25 construction as is the customary practice; so as shown on the drawings the advancing means comprises a sectional screw conveyor including the sections 20 and 21 of substantially the same length universally connected at 22. To maintain the screw sections in proper position within the trough 14 and to avoid buckling or swinging motion thereof, the bearing member 23 is provided. Heretofore, the use of a bearing member in a fuel conveyor has restricted the free passage 25 of the coal. This restriction results in what is known as a boiling action of the coal. In other words, the coal accumulates in the zone of the bearing member sufficient to pack under the slide plates 24 causing excessive force to revolve the 30 screw conveyor and insufficient delivery of coal. To obviate this difficulty the vane 21a of the screw section 21 adjacent the bearing member 23 is enlarged as indicated at 25.

Should this enlarged vane be extended much 35 beyond the bearing 23 or used on the rearward end of the screw section 20, the coal would be conveyed to the crusher 26 more rapidly than the enlarged portion 27 of the vane 20a, would carry the coal away. Therefore, the screw conveyor is constructed throughout its length in such a manner that the rearward flights will convey forwardly no more coal than can be carried away by the vanes 27.

The enlarged vane 25 is of sufficient size and 45 capacity to advance the coal under the bearing member 23 to avoid boiling or any restriction to the free flow of the coal from a point rearward to a point forward of the bearing. In order to utilize the enlarged vane, the arcuate bottom 40 and the sidewalls of the trough 14 are offset as at 28 opposite the vane 25. From Figure 3, it will be observed that the arcuate portion 29 of the bearing member closely fits the enlarged vane 25 to prevent lateral movement thereof, 50 55

while at the same time, permitting free passage of the coal directly under the arcuate portion and at each side thereof through the channels 30 and 31. Preferably, the bearing member 23 is disposed slightly rearward of the universal joint 22 so that access may be had thereto. In practice the rearward portion of the vane 21a of the screw section 21 will advance materially less coal than can be easily moved forward by the enlarged vane portion 25 and in like manner the rearward end portion of the vane 20a of the screw section 20 will advance no greater amount of coal than can be moved forwardly by the enlarged vane portion 27. It will be understood that the capacity of the rearward end portion of the screw section 20 is at least equal to or preferably, slightly in excess of the capacity of the rearward end portion of the screw section 21.

The screw conveyor is driven from its rearward end by the gear 32 and the pinion 33 disposed in the water tight housing 34 formed with the trough 14. The pinion is mounted on a shaft 35 coupled at 36 to the forwardly extending drive shaft 37 extending forwardly through the transverse wall 38 of the trough forming a part of the front wall of the tender. Since the drive shaft 37 is disposed in the water compartment, means is provided to form a seal at its forward end to prevent loss of water through the front wall of the tender and similar means is provided to form a seal on the shaft 35 to prevent passage of water into the gear housing 34. For this purpose as best shown in Figures 2 and 4, the shaft 37 passes through a packing box comprising the inwardly cylindrical extension 40 of the trough front wall 38 containing a bushing 41 and the packing gland 42. Suitable packing is interposed between the gland and the bushing as indicated at 43. A similar packing box is formed with the housing 34 for the purpose heretofore explained. This box comprises a gland 45 on the pinion shaft 35 to compress suitable packing as at 46 against the bushing 47 contained in the cylindrical extension 48 of the housing. An aperture 49 in the bushing 41 registers with a drain pipe 50 extending downwardly through the tender underframe exterior of the water compartment. Any leakage of the water through the packing 46 will pass through the drain pipe 50 and thus not enter the gear housing. This construction has the advantage that the dripping of water from the drain pipe will serve as an indication that the packing gland must be tightened or the packing replenished. Each of the packing glands 42 and 45 may be provided with fastening bolts as at 51.

Those familiar with the art will recognize that the described structure provides a novel locomotive tender and fuel conveying mechanism of increased coal and water carrying capacities and wherein the fuel advancing means may be made in sections and provided with a suitable bearing without causing any restriction to the desired conveyance of the coal.

I claim:

1. In a locomotive tender having a water storage compartment and a fuel bunker, the combination of partition plates between the compartment and bunker, a stoker trough in communication with the bunker and disposed within the compartment so that it will contact the water therein, said trough and partition plates forming a water tight partition between the compartment and the bunker, a conveyor screw in said trough, and a bearing member disposed in the trough and

mounted over a portion of the screw intermediate the ends thereof, that portion of the screw underneath the bearing member formed with vanes of greater diameter than the vanes of the screw adjacent each side of the bearing member, the walls of the trough opposite that portion of the vane underneath the bearing member being recessed to receive the enlarged vane portion of the screw, a housing at the rear of the trough enclosing gearing for driving the screw, and a drive shaft operatively connected with said gearing.

2. In a locomotive tender having a water storage compartment and a fuel bunker, the combination of partition plates between said compartment and bunker, a stoker trough in communication with the fuel bunker and disposed within the compartment so that it will contact the water therein, said trough and partition plates forming a water tight partition between the compartment and the bunker, conveying means in said trough comprising a rear screw section and a forward screw section, means flexibly connecting said sections at their adjacent ends, a bearing member disposed in the trough rearward of said connecting means and positioned to extend over the forward end portion of the rearward screw section, that portion of the rearward screw section underneath the bearing member being of greater fuel carrying capacity than the rearward portion of said section and of the rearward end portion of the forward screw section, a housing at the rear of said trough enclosing gearing for driving said conveying means, and a drive shaft operatively connected with said gearing.

3. In a locomotive tender having a water storage compartment and a fuel bunker, the combination of partition plates between the compartment and bunker, a stoker trough in communication with the bunker and disposed within said compartment so that it will contact the water therein, said trough and partition plates forming a water tight partition between the compartment and the bunker, conveying means in said trough comprising rearward and forward screw sections, means flexibly connecting said screw sections at their adjacent ends, a bearing member disposed in said trough rearward of said connecting means and disposed over the forward end portion of the rearward screw section, said forward end portion of the rearward screw section being of greater fuel carrying capacity than the rearward portion of said section and being also of greater fuel carrying capacity than the rearward portion of said forward screw section, the forward portion of said forward screw section being of greater fuel carrying capacity than the rearward portion of each of the screw sections, and drive mechanism associated with said conveying means.

4. In a locomotive tender having a fuel bunker, the combination of a stoker trough mounted on the tender in communication with the bunker and disposed thereunder, conveying means in said trough comprising rearward and forward screw sections, means flexibly connecting said screw sections at their adjacent ends, a bearing member disposed in said trough rearward of said connecting means and disposed over the forward end portion of the rearward screw section, said forward end portion of the rearward screw section being of greater fuel carrying capacity than the rearward portion of said section and being also of greater fuel capacity than the rearward

portion of said forward screw section, the forward portion of said forward screw section being of greater fuel carrying capacity than the rearward portion of each of the screw sections, and 5 drive mechanism associated with said conveying means.

5. In combination, a fuel bunker having an elongated opening for the discharge of fuel therefrom, a plurality of slidable plates controlling the 10 discharge of fuel through said opening, a trough disposed below said plates in a position to receive fuel discharged through said opening, conveying means in said trough comprising rearward and forward screw sections flexibly connected at their 15 adjacent ends, and a bearing member mounted in said trough over the forward end portion of the rearward screw section rearward of the flexible connection between the sections, that portion of the rearward screw section beneath said bearing 20 member being enlarged with respect to the rear-

ward end portion of the section, the enlargement being of a size sufficient to increase the carrying capacity thereof to prevent boiling of the fuel against said slide plates directly rearward of the bearing member.

6. In a locomotive tender having a fuel bunker, a stoker trough in communication with the bunker, a conveyor screw in said trough, and a bearing member disposed in the trough and mounted over a portion of the screw intermediate 10 the ends thereof, that portion of the screw underneath the bearing member formed with vanes of greater diameter than the vanes of the screw adjacent each side of the bearing member, the 15 walls of the trough opposite that portion of the vane underneath the bearing member being recessed to receive the enlarged vane portion of the screw.
